ATTORNEY

UNITED STATES PATENT OFFICE.

WILBUR J. COMPTON, OF OGDEN, UTAH.

CONDIMENT HOLDER.

Application filed April 10, 1925. Serial No. 22,145.

This invention contemplates the provision of a combination salt and pepper shaker including a slide valve capable of being conveniently manipulated, so that the contents of either condiment compartment can be used when desired, the invention providing an article of the class in question which is simple in construction, artistic in appearance and one which can be cheaply manufactured and sold.

The nature and advantages of the invention will be better understood when the following detailed description is read in connection with the accompanying drawing, the invention residing in the construction, combination and arrangement of parts as claimed.

In the drawing forming part of this application, like numerals of reference indicate similar parts in the several views, and wherein:

Figure 1 is a vertical sectional view through the invention.

Figure 2 is a sectional view on line 2—2 of Figure 1.

Figure 3 is a top plan view.

Figure 4 is a sectional view taken on line 4—4 of Figure 1.

Figure 5 is an enlarged fragmentary sectional view showing the valve in position reverse to that shown in Figure 1.

Referring to the drawing in detail, 10 indicates a receptacle which may be constructed from any suitable material and vary in size and contour without departing from the spirit of the invention. The receptacle is preferably constructed of glass and is divided by a partition 11 into separate condiment compartments 12 and 13 respectively, and it will be noted upon inspection of Figure 1 that these compartments are adapted to be filled from the bottom of the receptacle through suitable openings provided therein, which openings are normally closed by removable stoppers 14. The receptacle is closed by means of a cover 15 suitably perforated, the perforations 16 above the compartment 12 being smaller than the perforations 17 above the compartment 13. The partition

11 terminates in spaced relation to the upper edge of the receptacle to provide a space for the slide valve 18, the latter being mounted directly beneath the cover 15 to close either series of perforations 16 and 17 respectively. It will be noted upon inspection of Figure 1 that the receptacle is formed with an in-

ternal bead or flange 19 which is spaced from the cover 15 a distance to support the valve 18, so that this valve will nicely fit between the flange and cover in the manner illustrated. As hereinabove stated, the valve 18 is adapted to be shifted to occupy a position at either side of the partition 11, so that the contents of either compartment can be used, and the supply from the other compartment cut off.

For this purpose, I preferably employ a lever 20 which is fulcrumed upon a transverse shaft 21 arranged within the receptacle, the upper end of the lever being pivotally connected to the valve 18 as at 23. The lower end of this lever is connected with one end of a spring 24, the other end of which is connected with the receptacle, the spring being utilized to normally hold the valve 18 in the position shown in Figure 1. The lever 20 is also connected with the inner end of a push rod 25, the outer end of which is provided with a knob or thumb engaging portion 26 which operates in a suitable depression 27 formed in one side of the receptacle 10, the thumb engaging portion normally lying substantially flush with the outer surface of the receptacle. When the valve 18 occupies the position shown in Figure 1, the contents of the condiment compartment can be used without any danger of the contents escaping from the compartment 12. However, when it is desired to use the contents of the compartment 12, it is only necessary to push inwardly on the thumb engaging member 26, thereby reversing the position of the lever 20, which causes the valve 18 to shift to the position shown in Figure 5, thereby uncovering the perforations 16 in the cover and closing the perforations 17 thereof.

While it is believed that from the foregoing description, the nature and advantages of the invention will be readily apparent, I desire to have it understood that I do not limit myself to what is herein shown and described, and that such changes may be resorted to when desired as fall within the scope of what is claimed.

Having thus described the invention, I claim:

A condiment holder, comprising a receptacle divided into separate compartments, a cover having a group of perforations for each compartment, an inwardly directed flange formed on the receptacle immediately

2
beneath said cover, a slide valve operating on said flange and adapted to normally close the perforations of one group, said valve having an opening, a pin extended 5 across said opening, a vertically disposed lever arranged within one compartment and pivoted at a point between its ends, the upper end of said lever being bifurcated and receiving said pin, a coiled spring terminally 10 connected to the receptacle and the other end of said lever, a pocket formed in the

receptacle and projecting inwardly therefrom and having a central opening, a push-rod slidable thru said opening and having a slot and pin connection with said lever 15 at an appropriate point in its length and a head carried by said rod and operating in said pocket as and for the purpose specified.

In testimony whereof I affix my signature.

WILBUR J. COMPTON.
